CLAIM

The ornamental design for a gift card with greeting card, as shown and described.

DESCRIPTION

FIG. 1 is a perspective view of the gift card with greeting card of the present invention.

FIG. 2 is a front view of the gift card with greeting card of FIG. 1.

FIG. 3 is a rear view of the gift card with greeting card of FIG. 1.

FIG. 4 is a top-down view of the gift card with greeting card of FIG. 1.

FIG. 5 is a bottom-up view of the gift card with greeting card of FIG. 1.

FIG. 6 is a left side view of the gift card with greeting card of FIG. 1; and,

FIG. 7 is a right side view of the gift card with greeting card of FIG. 1.

The broken lines are for the purpose of illustrating the environment of the design only and form no part of the claimed design.
